TIE COLLAR EXTENSION CLIP OR CLAMP

Gerard C. Yoder, Brooklyn, N. Y.

Application May 4, 1948, Serial No. 25,003

3 Claims. (Cl. 24—81)

1

This invention relates to an extension clip or clasp for tie collars, and particularly to a clip capable of being adjusted to extend the length thereof.

The main object of the invention is to provide an extension clip or clasp of the character indicated having a manually-adjustable nut for adjusting the length and extending the clip to fit various sizes of tie openings on collars.

Another object is to have such an extension clip or clasp which has collar-gripping or clasping means which retain their gripping character unaltered despite longitudinal adjustment of the clip as a whole.

A further object is to have an extension clip or clasp of this type in which the adjusting nut engages with two intermediate right and left hand threaded portions, while two other portions slidably engage with an intermediate-located guide member for maintaining the main clasp members properly aligned.

It is also an object to have such a clip or clasp upon which the adjusting nut may be ornamented to disguise its nature and enhance the appearance of the clasp as a result.

An ancillary object is to make a clasp or clip of the mentioned type which is thoroughly mechanical in nature but nonetheless as thoroughly ornamental in form and design.

Other objects and advantages of the invention will appear in further detail as the specification proceeds.

In order to facilitate ready comprehension of this invention, the latter is illustrated on the accompanying drawing forming part hereof, and in which:

Figure 1 is a plan view of a tie collar extension clip or clasp made according to this invention and embodying the same in a practical form;

Figure 2 is a front elevation of the same tie collar extension clip or clasp;

Figure 3 is a longitudinal section taken on line 3—3 in Figure 2;

Figure 4 is a vertical section taken on line 4—4 in Figure 1;

Figure 5 is a fragmentary plan view of a modification of the tie clasp;

Figure 6 is a vertical section taken on line 6—6 in Figure 5.

In the six views, the same reference numerals indicate the same or like parts.

It is well known among men that shirts and collars differ widely although they may apparently be of the same size, and particularly is this true of a tie opening upon the collars of these

2

shirts. If we add to that the fact that ties also differ, some requiring larger openings than others and actually being more bulky than others when tied, it is readily seen that the collar in

5 which a tie is arranged may either have a wide opening originally or may be forced widely open by the type of tie used. On the other hand, the tie may be more or less thin and the knot thereof as a result will also not occupy any great space so that the tie opening in the collar upon which it is arranged will perhaps not be very widely separated, one collar member from the other.

In view of the fact that the collar opening in the front for accommodating the tie is thus variable, it is simply a matter of common sense to have either a series of tie clasps and collar clips, etc., which are of series of different lengths, or else have one collar clip or clasp which is extensible by manually adjusting the same.

10 In view of the desirability for having such an extensible clip or clasp, I have found it feasible to construct such a device which is not only practical, but susceptible of considerable ornamentation and variation, as will now be specifically set forth.

15 In the practice of my invention, and referring again to the drawing, a tie collar extension clip or clasp, generally indicated at 7, mainly comprises a bracket member 8 which is substantially tubular in form and provided at the end thereof with a pair of substantially parallel, forwardly-projecting arms 9, 9 through the apertures 10, 10 of which a pair of aligned clasp members 11, 11 extend. The inner ends of these clasp members are threaded at 12, 12, the one with a right-hand thread and the other with a left-hand thread, while upon these threads is mounted a correspondingly internally-right-hand and left-hand threaded nut 13 which may externally be smooth, knurled or ornamented in any manner desired. The outer ends 14, 14 of the mentioned clasp members 11, 11 are bent rearwardly and terminate in a pair of balls or knobs 15, 15. The mentioned clasp members 11, 11 are preferably 20 of round cross-section, making them suitable to receive the threads 12, 12 already mentioned.

25 A pair of secondary clasp members 16, 16 of substantially square cross-section extend slidably into the previously-mentioned member 8 which serves as a guide for the same, and beyond the latter member 8 the secondary clip or clasp members 16 are bent forwardly at 17, 17 toward the first-mentioned clip members 11, 11 and soldered to the latter within the ends 14, 14 thereof at 18, 18. Beyond the forwardly-bent portions 17, 17

the secondary clip members are abruptly bent rearwardly again to form the rear clasp heads 19, 19 juxtaposed to the previously-described knobs 15, 15, and serving to cooperate therewith to clasp the ends of a collar therebetween.

In Figures 1, 2 and 3, the clasp members 11, 11 and 16, 16 are disposed in their innermost contiguous positions to serve as a clasp upon a collar with a substantially narrow opening at the tie, but the device is adjustable by rotating nut 13 in such fashion as to separate the two clasp members 11, 11 from each other due to the presence of the right and left hand threads on the inner ends of said clasp members, with the result that the latter may extend as far as indicated in broken lines in Figure 3, adapting the device to a collar with a very wide tie opening. As the nut 13 separates the front clasp members 11, 11, the rear or secondary clasp members 16, 16 are also separated due to the fact that they are soldered to the front clasp members and therefore slide in tubular member 8 to have corresponding movement with the threaded members 11, 11 which are directly engaged and moved by the nut 13. Any adjustment between the two thus shown in full lines and broken lines in Figure 3 may be attained by rotation of nut 13 in either one direction or the other, as required. It is easily seen that the knob 15 and rear clasp member or terminal 19 at each end of the device constitute a collar-gripping jaw individually capable of gripping or clasping the end of a collar at the tie opening and retaining its position in relation thereto by friction therewith. It is likewise readily seen that no matter what the adjustment of the front and rear clasp members 11 and 16 may be, the relations between the clasping ends 15 and 19 of the device will remain exactly the same.

It has already been mentioned that the bent portions 17 projecting forwardly from the rear clasp members 16 are soldered to the front clasp members 11. This may, of course, include brazing or welding or fastening thereto by any means known in the art. On the other hand, actual fusing of metal for securing the forwardly-bent portions 17 of clasp members 16 against or with the front clasp member 11 at each side is not necessary, inasmuch as an outside metal band or link may be used as particularly shown in Figures 5 and 6. Thus, in these figures the rear member 8 is provided as before with a forwardly-extending arm 9 (only one shown), and the front and rear clasp members 21 and 26 (only one of each being shown). Each front member 21 has, of course, a bent member 24 terminating rearwardly in the ball or knob 25, while the rear clasp members 26 each have a forwardly bent portion 27 and beyond the latter a rearwardly-bent gripping head or portion 29. In each case the forwardly-bent portion 27 on rear clasp member 26 is secured to the front clasp member 21 by means of a ring or band 28.

In the last-described form, the extension clip or clasp is similar to that shown in the first three figures as well as in the section of Figure 4 with respect to the clasp members 21 and 26, as they are similar to previously-described clasp members 11 and 16, but the previously-described soldered portion 18 is replaced by the mentioned ring or band 28. In both forms of the clip or clasp, it is, of course, possible to decorate the nut 13 and the forwardly-extending arms 9, as well as the front clasp members 21 and the device may be partly made of precious metals or wholly made thereof or plated therewith.

It is also true that in both forms the same operation holds true that rotation of nut 13 will cause not only the front clasp members to separate or approach each other within the nut, but also the rear clasp members 26 will either recede from each other or approach toward each other, depending on the direction of rotation of nut 13 and the corresponding movement of clasp members 21.

10 Manifestly, other variations may be resorted to and parts and features may be modified or used without others within the scope of the appended claims.

Having now fully described my invention, I claim:

15 1. A tie collar extension clip or clasp including an elongated tubular guide member having a pair of mutually parallel arms rigidly projecting substantially at right angles from the ends toward one side thereof, there being apertures in both arms, a pair of aligned front clasp members having their mutually-adjacent ends extending through the apertures in said arms and being threaded with a right hand thread and a left hand thread respectively, a rotatable elongated nut correspondingly internally threaded with right hand and left hand threads mounted upon the threaded ends of the front clasp members, outwardly-extending and rearwardly-bent portions upon the latter terminating in collar-engaging knobs or ends, a pair of rear clasp members of substantially right-angular cross-section having aligned portions extending slidably into the ends of the elongated tubular guide member, a forwardly-directed portion upon the outer end of each of the aligned portions of the rear clasp members, means securing the forwardly-directed portion of each rear clasp member to the respectively adjacent front clasp member, and a rearwardly and outwardly-directed portion extending from each forwardly-directed portion of said rear clasp member terminating in a collar-engaging head or end disposed in juxtaposition to the respectively adjacent collar-engaging knob of one of said front clasp members for clasping the ends of a collar therebetween.

20 2. A tie collar extension clip or clasp including an elongated tubular guide member having a pair of mutually parallel arms rigidly projecting substantially at right angles from the ends toward one side thereof, there being apertures in both arms, a pair of aligned front clasp members having their mutually-adjacent ends extending through the apertures in said arms and being threaded with a right hand thread and a left hand thread respectively, a rotatable elongated nut correspondingly internally threaded with right hand and left hand threads mounted upon the threaded ends of the front clasp members, outwardly-extending and rearwardly-bent portions upon the latter terminating in collar-engaging knobs or ends, a pair of rear clasp members of substantially right-angular cross-section having aligned portions extending slidably into the ends of the elongated tubular guide member, a forwardly-directed portion upon the outer end of each of the aligned portions of the rear clasp members, the forwardly-directed portion of each rear clasp member being soldered to the respectively adjacent front clasp member, and a rearwardly and outwardly-directed portion extending from each forwardly-directed portion of said rear clasp member terminating in a collar-engaging head or end disposed in juxtaposition to the respectively adjacent collar-engaging knob of one

of said front clasp members for clasping the ends of a collar therebetween.

3. A tie collar extension clip or clasp including an elongated tubular guide member having a pair of mutually parallel arms rigidly projecting substantially at right angles from the ends toward one side thereof, there being apertures in both arms, a pair of aligned front clasp members having their mutually-adjacent ends extending through the apertures in said arms and being threaded with a right hand thread and a left hand thread respectively, a rotatable elongated nut correspondingly internally threaded with right hand and left hand threads mounted upon the threaded ends of the front clasp members, outwardly-extending and rearwardly-bent portions upon the latter terminating in collar-engaging knobs or ends, a pair of rear clasp members of

substantially right-angular cross-section having aligned portions extending slidably into the ends of the elongated tubular guide member, a forwardly-directed portion upon the outer end of each of the aligned portions of the rear clasp members, a ring or band encircling the forwardly-directed portion of each rear clasp member and the respectively adjacent front clasp member, and a rearwardly and outwardly-directed portion extending from each forwardly-directed portion of said rear clasp member terminating in a collar-engaging head or end disposed in juxtaposition to the respectively adjacent collar-engaging knob of one of said front clasp members for clasping the ends of a collar therebetween.
